[57] CLAIM

The ornamental design for a bottle, as shown and described.

DESCRIPTION

FIG. 1 is a perspective view of our new bottle;
FIG. 2 is a top plan view thereof;
FIG. 3 is a bottom plan view thereof;
FIG. 4 is a front elevation thereof, the appearance of the
claimed design repeats three times around the central vertical
axis of the bottle; and,
FIG. 5 is a right side elevation thereof.The broken lines showing the bottle neck and base are for
illustrative purposes only and do not form part of the
claimed design.
